UNITED STATES PATENT OFFICE.

CLYDE SMITH, OF CLEVELAND, OHIO, ASSIGNOR, BY MESNE ASSIGNMENTS, TO
FREDERICK C. STEVENS, OF ATTICA, NEW YORK.

TELEPHONE SYSTEM.

1,137,360.

Specification of Letters Patent. Patented Apr. 27, 1915.

Application filed April 4, 1911. Serial No. 618,926.

To all whom it may concern:

Be it known that I, CLYDE SMITH, a citizen of the United States, residing at Cleveland, in the county of Cuyahoga and State of Ohio, have invented certain new and useful Improvements in Telephone Systems, of which the following is a specification, reference being had therein to the accompanying drawing.

10 My invention relates to telephone exchange systems, and especially those of semi-automatic type as shown in application to J. L. Wright, Serial No. 612,738, filed March 7, 1911.

15 It has for its object the improvement of such systems in divers particulars.

In order to render possible complete supervision of the mechanical operation of the system, I provide group lamps for the line 20 relays, individual lamps for selector and connector switches, including the primary and secondary selectors, and an individual lamp for the operator's listening key. In order to prevent a calling line from reaching more than one operator, by accident or intent, I provide a self-locking line relay, which when once energized will remain locked on a local circuit extending through back contacts on the cut-off relay, until said 25 cut-off relay is energized. In order that the operator may be apprised of the condition of such a line when the calling subscriber has already hung up his receiver before the operator answers, I provide a special tone- 30 test in the primary selector circuit, which becomes operative only under the condition which it is meant to indicate. As an improvement in the means for releasing the secondary selector switch and disconnecting 35 the operator from a completed conversation circuit between subscribers, I provide special means on the key set distributing switch, which determines the order and destination 40 of the current impulses from the sending machine, said means becoming operative after one complete cycle of operation of the 45 sending machine and the switch, to close the release circuit of the secondary selector switch.

50 My invention is illustrated in the accompanying drawings, showing a complete system embodying the same, and the principal pieces of apparatus, used therein.

In the drawings: Figure 1 is a skeleton 55 diagram of the complete system shown in

detail in Figs. 2 to 6 inclusive. Fig. 2 is a diagram showing the subscribers' line and the primary control circuits at the central office. Fig. 2^a is a modification of the kick-off switch control. Fig. 3 is a diagram showing the primary and first selector switch circuits. Fig. 4 is a diagram showing the connector switch circuit. Fig. 5 is a diagram showing the operator's trunk with key-set control circuit. Fig. 6 is a diagram showing the operator's key-set and sending machine circuit. Fig. 7 is a diagram showing a party line circuit accessible from the connector of Fig. 4. Fig. 8 is a diagram showing a detail of secondary call distribution for simultaneous calls.

In this description I will first outline the system as shown in Fig. 1, and then take up the circuits in Figs. 2 to 6 inclusive, and explain their operation in detail.

In Fig. 1, each element is marked with the title by which in general it will be designated throughout the case, and enough of the reference letters and numerals are shown for purposes of comparison and to gain a general understanding of the relation of the various parts of the circuits shown in the other diagrams. It may be here stated that for convenience all calls will be assumed to originate at the left hand end or station, and all connections to progress toward the right, the wanted or called subscriber being assumed as the right hand subscriber in every case. Of course, it will be understood that there is no such limitation in practice, but this assumption simplifies description and illustration. In this figure therefore three subscribers are shown at the left hand end of the sheet whose lines terminate on multiple contacts of three primary selector switches, each of which has a pivoted wiper or contact which can be swept over the line contacts to connect with any one of them. Each of these wipers forms one terminal of a first selector trunk, the other terminal of which is a similar wiper in the first selector switch. The fixed contacts over which these wipers sweep in all the switches are usually referred to as bank contacts, and in mass as "contact banks." The bank contacts of the first selector switches form the terminals of second selector trunks, each of which is connected to corresponding contacts, that is to say "multiplied", in all the first selectors. At the right hand ends the second selector 100

trunks terminate at wipers of second selector switches, and from the bank contacts of these switches the connector trunks are taken, in multiple as before, to the wipers of connector switches. The banks of these connector switches contain only line terminals, just the same as the primary selectors. At the right hand end of Fig. 1 three subscribers' lines are shown, each with four subscribers' stations connected to it in parallel. These are party lines, so shown for the purpose of illustrating the principle of selective ringing, which forms a part of the system. They need not all be party lines however, nor is it necessary that the subscribers shown on the right of Fig. 1 should be different from those shown at the left. On the contrary, every subscriber's line, in order to have complete service, must be connected to terminals in both the primary selector switches and the connector switches, since it is through the former that the subscriber when calling reaches the central office, and it is through the connector switches that the central office when calling reaches the subscriber. The connections of a line to primary and connector switches are made in parallel, just as are those of each line to the several switches of either class. Associated with each connector switch is an auxiliary or ringing selector switch. The wiper of this switch sweeps over contacts connected to several ringing generators, each of which generates a particular distinctive character of current. At the several stations on a party line the bells are designed and adjusted so as to respond selectively and exclusively, each to its own particular kind of current only. At the last stage in a connection, when the wanted subscriber's line has been picked out by the connector switch, and the ringing selector has been set so as to bring into service the proper generator, the wiper of that switch is then automatically connected through the connector to the subscriber's line to ring the bell. At all other times the ringing selector remains disconnected.

The primary selector switches are controlled by the subscribers in calling, through the medium of line relays at the central office which respond to the flow of current in the subscribers' lines, and which when so energized guide and direct the primary switch wipers to their respective line contacts. A calling subscriber therefore gains access to the first selector trunks in the central office by his own act alone. In order to continue the connection however, from the first selector trunk to the wanted subscriber, it is necessary to actuate a first selector switch, a second selector switch and a connector switch. The type of switch employed in this system is electromagnetically driven by means of current impulses of predetermined

number sent in predetermined groups, which move the switch wipers step by step over the bank contacts. These impulses are supplied, and the switches are controlled, by operators at the central office, who for that purpose are given access through secondary selector switches to the first selector trunks, whereby they are enabled both to receive their orders from the calling subscribers, by way of the primary selectors, and to send impulses to the first selector and succeeding switches, for the purpose of making the desired connection. The secondary selector switches as will presently be seen, are initially responsive to the subscribers' acts in calling. In fact, broadly speaking, their operation is the same as that of the primary selectors, the flow of current in a calling subscriber's line and in the first selector trunk connected thereto causing a secondary selector switch wiper to be guided and directed automatically to a contact in its bank which is connected to the first selector trunk in question.

In order to select and transmit the proper impulses for line selection I provide each operator with a key-set mounted on a suitable desk, and having associated with it certain signals which guide the operator in the performance of her duties. The key-set in general appearance and arrangement is quite similar to the key board of an adding machine or typewriter, consisting of a number of strips of ten keys each, numbered from one to naught in each vertical row. One of the signals associated with these keys is a calling lamp, which is lighted automatically when the key set becomes connected through the secondary switch to a first selector trunk already connected to a subscriber's line through a primary selector switch. Observing the signal, the operator asks the subscriber for the number wanted, and proceeds to depress the correspondingly numbered keys or buttons. She then presses a separate starting key, and groups of impulses, corresponding to the buttons depressed, will thereupon be transmitted through the key-set, through the secondary selector switch, and through the first selector trunk to the first selector switch, causing the following operations: (1) the first selector switch is stepped around to the contact of a second selector trunk leading to a second selector switch in the thousands group corresponding to the first digit set up; (2) the second selector switch is stepped around to select a connector trunk leading to a connector switch of the hundreds group corresponding to the second digit set up, (this particular connector containing terminals of the line wanted); (3 and 4) the connector switch is then stepped around in response to the third and fourth groups of impulses to pick out the terminals of the line wanted; and (5) the associated ringing

selector having been set in response to the operation of the impulses, the wanted subscriber's bell is automatically rung.

Reference has been made above to "thousands groups" and "hundreds groups" of circuits. This particular switching system is known as a percentage trunking system. That is to say, the connection between any two lines is effected by successive steps or successive acts of subdivision. For example, in an exchange serving ten thousand subscribers, the second selector switches would be divided into ten groups, through one of which access could be had to the connectors containing lines numbered from 1000 to 1999, through the next to lines numbered from 2000 to 2999, and so on. Similarly, the connector switches in each thousands group would be divided into ten sub-groups according to their hundreds digit. Through the first of these sub-groups, lines numbered from 100 to 199 could be reached, through the second lines numbered from 200 to 299, and so on. Obviously therefore, access could be had to any desired line by selecting first a second selector of the thousands group in which that line number occurs, and then by means of that selector picking out a connector of the hundreds group in which the line number occurred. That connector would then actually contain terminals of the wanted line. Of course in practice the wiring between the different groups of switches is quite complicated because of the large number of trunk wires employed to furnish the various combinations required between the switches, but the theory is quite simple, and is well enough illustrated in Fig. 1. As soon as one of the subscribers at the left of Fig. 1 has become connected in the manner stated with one of the subscribers at the right, it is unnecessary and in fact undesirable for the operator to remain longer in connection with them, and means are provided for automatically cutting off and restoring the secondary selector switch as soon as this condition is brought about. Thereafter all the switches in use between the two subscribers are under their own control, and when they finally hang up their receivers the several switches are automatically restored, the connection is broken, and all parts resume the positions of idleness diagrammatically illustrated in Fig. 1.

It will be noted after reading the foregoing, that portions of the apparatus and circuits at the central office are common to all or a number of subscribers' lines whereby confusion might arise from simultaneous connection of more than one line to the same trunk, more than one trunk to the same line, more than one trunk to the same operator, or more than one operator to the same trunk. Special provision is made however, to prevent this. At the left of Fig. 1

I have indicated what I call a primary distributing switch and a secondary distributing switch. The first of these contains in its banks testing terminals of the primary switches or first selector trunks. It is actuated in response to the subscribers' calls, and always acts to select and start up an idle switch and trunk for connection with the calling line. There is only one distributing switch for all the primary selector switches serving the same group of subscribers, hence only one switch can be started at a time, and this prevents more than one trunk being connected to the same line. In going to the line, the action of the primary switch is to test over its bank contacts until it reaches a contact which has had its condition changed, due to current flowing in the calling line. If more than one line is calling, the switch will stop at the first one to be reached, and thereafter the distributing switch will start another primary selector to search for the second calling line, whereby it is impossible for more than one line to get on the same trunk. The secondary distributing switch performs the same functions with respect to the operators' or secondary selector switches, and is actuated also in response to the subscribers' calls, so as to start only one secondary selector switch at a time for any one group of trunks.

As no claims will be made herein to the mechanical features of the apparatus employed, detailed description thereof is unnecessary; and the construction and functioning of the several pieces will be sufficiently understood from the detailed statement of operation hereinafter, read in connection with the following remarks: The unit of the connective system is a one hundred point switch, of the same type as that shown in Letters Patent No. 977,536, granted December 6, 1910, to Charles H. North. The primary and secondary selector switches shown in diagram in Figs. 3 and 5 require a row test wiper on the spindle in addition to those shown in the North patent, but this may be affixed to the spindle in any suitable way, being of course insulated therefrom. The function of this wiper as it is shown at w^{26} and w^{82} in Figs. 3 and 5 respectively, is to pick out the row of contacts in which the individual contacts of a calling line or trunk may be found. This is done during the first or rotary motion of the spindle, and when the busy or calling row-contact is found, the switch stops rotating and starts to step up the row designated. The lower or test contacts w^{25} , w^{83} and w^{84} , in Figs. 3 and 5 respectively, then slide up the row of individual test contacts until the particular calling contact is reached, when all motion ceases, and as the connective or talking contacts w^3-w^4 , $w^{80}-w^{81}$ (Figs. 3 and 5) move constantly with the test wipers and are alined

Hereby, the calling line or trunk is thus accurately selected and connected. The relays throughout the system are preferably of the type shown and described in Letters Patent No. 1,072,641, granted October 11, 1913, to Charles B. North; but any standard relay may be adopted to this service. The operator's keys employed as shown in Fig. 6 are built in strips, are interlocking, and a plurality of the general type shown in Letters Patent No. 955,134, granted April 10, 1909, to John F. Cadell; but obviously other standard interlocking keys may be adopted for this service.

15 The distributing switches shown at S, S¹, S², S³ and S⁴ in Figs. 2, 5, 4 and 8, are single-motion step by step electromagnetically driven switches preferably having the driving magnets mounted as a unit on a 20 short frame secured to the contact bank. A compound form for both the bank and stepping magnet with its armature and pawl, is that shown in the aforesaid North patent. Since only the rotary ratchet and the 25 operating rotary magnet are employed, no circuit is taken off through the wipers or spindle, each row or set of contacts in the banks being accompanied by a continuous shaft contact constituting a return therefor, 30 and the wipers being in pairs adapted to bridge any one contact of the set with the common return.

The subscriber's apparatus forms no part of the present invention, except as it is included for completeness in description, and is of any usual or desired type adapted to common battery circuits.

The operator's sending machine employed herein is preferably common to the whole exchange and of the type shown in application of J. L. Wright, Serial No. 402,033, filed November 15, 1907.

Referring now to Fig. 2, and bearing in mind the general description of Fig. 1, each line circuit 1-2 is provided with a line relay R' and a cut-off relay R¹ which when energized disconnects the line relay R' and connects the tip and sleeve sides of the line to its multiple bank contacts in the primary 50 and connector switches of its group. The attraction of the armature r¹¹ of the relay R¹ connects ground to the individual test contacts of the primary switches S¹. The attraction of armature r¹² locks the relay R' 55 on short circuit to ground through armature r²² of relay R², which prevents interference by the subscriber in case he should move his receiver hook. The line relays R' are divided into groups of ten and the windings 60 of each group are connected in multiple to the winding of a relay common to the group, which when energized connects ground to the row contact of the primary switch through the armature r¹¹, thus designating 65 the group of lines calling, while the relay R'

designates the particular line in the group. Each group of one hundred lines is assumed to have access for calling purposes to ten primary selector trunks, such as shown in Fig. 3, and to be accessible for calling through ten connector switches such as shown in Fig. 4. Thus each line has twenty sets of multiple contacts, ten in primary selector banks, and ten in the connector banks. The primary distributing switch S¹ determines which trunk in the group of ten being idle, shall respond to any particular call in its group of lines; and one of these primary distributing switches is therefore required for each group of one hundred 80 lines, with its ten trunks. Associated with each primary distributing switch S¹ there is a secondary distributing switch S², and a kick-off switch S³. The function of the secondary distributing switch is to pick out an idle operator circuit and start the same for testing for the group of primary trunks over which the call originates. This can be done because there being only one switch S¹ for each group of one hundred lines, that is to say for each group of ten trunks such as shown in Fig. 3, and since it is convenient to arrange the contacts of each group of ten trunks in one and the same row in the secondary selector switches S² (Fig. 5), each 85 secondary distributing switch can therefore be directly identified with its own associated row of primary trunk contacts in each of the secondary selector switches. Furthermore, since each secondary distributing switch S² has a number of contacts in its bank, these contacts may be individually connected to several secondary switches, the use of multiples for this purpose in the switches S² being thereby avoided, and a great additional advantage gained, in that simultaneous calls may be distributed from different groups such as shown in Fig. 2 to different operators' circuits such as shown in Fig. 5 without interference even when the calls are absolutely simultaneous. The circuits by which this result is attained are shown in Fig. 8 stripped of the detail of the other figures. Assuming an exchange of one thousand lines in which there would be ten groups of lines and trunks, with one secondary distributing switch S² for each group, corresponding contacts s² and s²⁰ are multiplied in the ten switches and connected respectively to wires 221 and 73 leading to the various secondary switches S³. The contacts s²⁰ are not multiplied but are wired direct to the row contacts s²² of the secondary switches S². Number one switch S² belonging to a certain group has its first contact s²² wired to number one row contact of the first secondary switch S³, its second contact s²³ wired to number one row contact of the second secondary switch S³, and so on. Number two switch S² belonging to another 130

group has its first contact s^{20} wired to number two row contact of the first secondary switch S^8 , its second contact s^{20} wired to number two row contact of the second secondary switch S^8 , and so on.

In an exchange of one thousand lines the contact s^{20} of the tenth switch S^2 are wired to number ten row contacts of the secondary switches S^8 . If in an exchange of one thousand lines simultaneous calls should come in from each group of one hundred lines and ten secondary selector switches S^8 were provided, one row contact in each switch S^8 would be made active. Without any confusion each switch S^8 would test for its active row contact and then find the individual contact in the row. The individual test contacts would be multiplied in a group of secondary switches S^8 so that any switch S^8 in the group can pick out any trunk belonging to its group. The relay R^5 has one terminal of its winding connected to the wiper arm ws of the switch S . When the arm ws in rotating finds an idle primary switch S^4 the relay R^5 is energized in series with the relay R^{13} (Fig. 3) and opens the circuit of stepping magnet M_1 thus bringing the switch S to rest. The energizing of the relay R^5 causes the switch S^2 to immediately start to pick out an idle secondary switch S^8 . The switch S^4 can be testing for the calling line while the switch S^8 is testing for the trunk shown in Fig. 3. The relay R^{13} acts somewhat as the line relay R' , connecting battery to its individual tests contacts in the switches S^8 .

It will be noticed in the statement of operation hereinafter that the relay R^{13} is not deenergized until the primary switch finds the calling line and the secondary switch S^8 finds the trunk connected to that line. By this arrangement all confusion is avoided regardless of which switch performs its functions first.

Referring to Fig. 3, the relay R^{12} is the row test relay, and is energized when the wiper w^{26} finds an active contact, disconnects rotary relay R^{18} and in its place connects vertical relay R^{19} . The relay R^{15} is used in testing for the individual contact as well as a battery supply relay for the calling subscriber. When energized this relay disconnects the row relay R^{12} . The deenergizing of relay R^{12} disconnects the relay R^{15} from the test wiper w^{25} and connects it to the sleeve wiper w^4 , in series with the cut-off relay R^2 . Relay R^{14} is the tip battery supply relay and controls the release magnets M^3 and M^4 after the first selector switch S^6 has moved off-normal. The relay R^{42} is used for opening the talking circuit while the impulses are being sent to operate the outgoing switches. This relay also with R^{15} jointly controls the relay R^{13} . Relay R^{41} is the test relay having its lock-

ing contact r^{413} connected to the test wiper w^{147} . Its circuit is initially closed through the contacts of relay R^{42} and foot springs 144 and 145. After the switch S^5 makes its first vertical step the circuit of this relay is maintained through contacts of relay R^{42} and test wiper w^{147} so long as this wiper encounters busy contacts, which are grounded through other switches.

Referring now to Fig. 4, relays R^{22} and R^{23} respond to impulses from the sending machine. Relay R^{23} receives the first set of impulses belonging to the connector and causes the stepping magnet M^{11} of the switch S^7 to step around so as to pick out generator current of the proper character. Operation of relay R^{23} closes the circuit of relay R^{24} whose locking contact r^{241} is connected to the bottom contact of relay R^{22} . Relay R^{23} also closes circuit of relay R^{27} . This latter remains energized until the called party answers or until the calling party hangs up his receiver. In case the called-for line is busy, relay R^{27} will be deenergized by action of test relay R^{29} . Relays R^{24} , R^{27} and R^{29} all have their circuits completed to ground side of battery through test wire 200, contacts c^{200} , w^{147} , 147, r^{413} to ground. When the calling party hangs up his receiver after failing to get his party, switches S^4 and S^5 are restored and ground removed from test wire, causing deenergization of any of the relays R^{24} , R^{27} or R^{29} which happen to be locked. The switch S^7 is restored to normal after the called subscriber hangs up his receiver or when the relays R^{25} , R^{27} and R^{24} are deenergized; and just before it reaches its normal position the wiper arm ws^7 passes over a contact and closes the circuit of the release magnet M^{12} restoring the connector switch S^6 to normal position. Thus the connector switch S^6 has a quick release if the called-for line is busy, and after the called party answers a slow release by switch S^7 which takes care of any accidental shaking of the receiver hook when the called party answers.

Referring to Fig. 5 relay R^{31} is the row test relay and R^{30} the individual test relay. Relay R^{32} is the control relay and corresponds to relay R^{13} (Fig. 3). Relay R^{34} is the signal relay and pulls up in series with relay R^{42} (Fig. 3) after the primary trunk has found the line and the secondary switch S^8 has found the trunk. The operation of this relay closes the circuits of the signal lamp L^3 (Fig. 6), the guard lamp L^2 and the night alarm bell. Relay R^{33} is the listening relay actuated by listening key LK . Operation of this relay deenergizes relays R^{32} and R^{42} and closes circuit of listening lamp L^4 . Relay R^{36} is the starting relay and is energized in series with R^{42} by the key SK . This relay disconnects relay R^{33} and connects the starting cam on the send-

ing machine to stepping magnet M^5 . It also closes circuit of guard lamp L^2 and disconnects battery from the first five contacts over which wiper ws^{200} sweeps. After 5 arm ws^{200} passes the fifth contact it encounters battery potential and relay R^{35} is energized and connects interrupter I to magnet M^{15} until arm ws^{200} reaches its normal position. Just before switch S^3 reaches normal position, cam springs 167, 168 are closed, completing the circuit of release magnet M^{15} , restoring switch S^8 to its normal position. Relay R^6 is the trunk start relay and is also used for release in case the calling subscriber hangs up his receiver or if the operator fails to get a response after pressing the listening key. This relay R^6 is energized by key RK , which also actuates relay R^{35} . These two relays being energized at the same time remove battery connection from the first two contacts over which arm ws^{200} sweeps. In trunk calls, such as to wire chief, toll board, etc., it is only necessary to operate the first selector switch, which with the present sending machine requires only two rotations of the drum. The trunks of this class are wired directly to certain bank contacts of the first selector switches and not to the connector banks, for quick trunk service. After arm ws^{200} passes the second contact the relay R^{35} is energized and operates as before. In case the calling party hangs up his receiver before the operator answers, relay R^{35} is energized in series with resistance coil r when the operator presses the listening key, which connects the tone test to the operator's telephone set, whereupon she presses the trunk start button RK . The first selector switch 40 S^5 upon receiving the first rotary impulse from the sending machine through one of the buttons of the strip K^2 closes the foot springs 175 and 176. The closure of these springs while relay R^6 is deenergized completes the circuit of release magnets M^2 and M^3 causing the release of switches S^4 and S^5 . Switch S^4 in restoring disconnects relay R^{15} which opens circuits of relays R^{14} , R^{36} and R^{37} . Relays R^{14} and R^{37} falling back connect battery to contacts ts^{200} to ts^{200} , energizing relay R^{35} to restore switch S^2 and S^8 . At any time during the building up of a connection the switches can be restored by the calling party in the manner described.

Referring to Fig. 6, number one key of each strip is connected to the pen on the sending machine which transmits one impulse at each rotation; number two key to that which transmits two impulses, and so on to number ten key which receives ten impulses. Each strip of keys has a common wire connected to one contact of each key in the strip and leading to its proper contact in the banks of the switch S^3 . The order in

which these are arranged to transmit impulses in proper sequence is as follows: At the first rotation of the sending machine the first strip of keys (hundreds) is connected to the tip side of trunk through switch arm ws^2 and contact ts^2 ; second rotation, ten test impulses from disk D^2 sent to sleeve side of trunk through arm ws^2 and contact ts^2 ; third rotation, selective ringing strip K^1 connected to tip side of trunk through arm ws^3 and contact ts^3 ; fourth rotation, keys K^2 (tens) connected to sleeve side through wiper ws^{200} and contact ts^2 ; fifth rotation, keys K^3 (units) connected to tip side of trunk through arm ws^3 ; during the fifth rotation and just after the units impulses have been set, a single test impulse is sent to sleeve side of trunk through disk D^3 , wiper ws^3 and contact ts^3 ; sixth rotation, arm ws^{200} engages contacts connected to battery energizing relay R^{35} . This relay unlocks R^{35} , restores switches S^2 and S^8 , thus disconnecting secondary switch S^8 from the primary trunk in Fig. 3.

The kick-off switch S' in Fig. 2 is provided for the purpose of preventing a defective trunk or operator's circuit from remaining connected to the calling line. In a word, it is a time controlled element started when a call comes in and operating after a predetermined interval longer than the time required for full operation of the switches S^1 and S^2 in Figs. 3 and 5 respectively, so that if the connection from the line in Fig. 2 through Fig. 3 into Fig. 5 is not complete, the switches are restored. The wipers ws^1 and ws^2 are swept over their bank contacts by stepping magnet M^1 , operated once at each rotation of the sending machine drum by closure of contacts d^{11} . The bank contacts are multiplied as shown, three contacts being left blank in each bank. The multiple contacts over which the wiper ws^1 sweeps are arranged one step in advance of the corresponding contacts over which wiper ws^2 sweeps. Relay R^6 is energized when switch S' picks out a secondary switch S^8 and partly closes circuit of magnet M^1 . When the cam on the sending machine closes springs d^{11} the circuit is completed and switch S' moves one step at each rotation of the sending machine. The maximum time for the secondary switch S' to pick out the trunk terminating on the tenth contact in the tenth row would permit about two rotations of the sending machine. As shown by the blank contacts in S' the minimum time element for three rotations has been allowed and the maximum for six, depending upon the position of the wipers of switch S' when relay R^6 is energized.

If wiper ws^1 has just passed multiplied contacts ts^{10} it will then require three steps of switch S' before wiper ws^1 finds battery potential to energize relay R^6 . In this case

it would require three more steps for wiper ws' to complete the circuit of relay R^6 . If wiper ws^{10} is resting on multiplied contact 18^{10} when relay R^6 is energized, it will require only three steps of wiper ws' before the circuit of the relay R^6 is closed. When relay R^6 operates it places ground on 218, 219, r^{51} , 31, M to battery, operating magnet M to step wiper ws to the next contact and thereby unlock the relay R^6 which in turn deenergizes relays R^{11} , R^9 and R^8 . The operation of relay R^6 also places ground on 218, 220, ws^2 , 221, r^{254} (Fig. 5), 122, 171, through release magnet M^{16} to battery, causing the release of secondary switch S^8 . If for any reason the secondary switch, after it is selected fails to make proper connection with the trunk in Fig. 3 so as to relieve relays R^{13} and R^5 , the kick-off switch will come into play and between three and six rotations of the sending machine cause secondary switch S^8 to be released and the switch S to pick out another trunk.

Operation: The subscriber at station A desiring a connection lifts receiver R from hook H which bridges his telephone across line wires 1-2, energizing relays R^1 and R^3 by way of B, 19, 20, R^3 , 21, R' , 22, r^{21} , 1, station A, 2, r^{22} , 23, ground to battery. Relay R' locks to ground through r^{11} , 24, and r^{23} , and connects ground to individual test contact c^{25} through 25 and r^{12} , while R^3 connects ground to row test contact c^{26} through 26 and r^{31} and completes circuit of group 35 lamp L and relay R^4 ; the former from B, 19, 27, L, 28, r^{32} , ground to battery, the latter from B, 19, 29, R^4 , 30, r^{33} , to ground. Lamp L lights, and relay R^4 completes circuit of stepping magnet M to interrupter I for intermittent energization over the path, B, 19, M, 31, r^{51} , 32, r^{41} , 33, I to ground. Magnet M moves switch S step by step until wiper ws engages a contact s connected to relay R^{13} (Fig. 3) of an idle primary selector trunk, whereupon relays R^5 and R^{13} , (Figs. 2 and 3) are energized by current through B, (Fig. 3), 34, 35, 36, r^{151} , 37, R^{12} , 38, (38 Fig. 2), s, ws , 39, R^6 , 40, r^{42} , to ground. Relay R^5 opens circuit of magnet M at r^{51} , locks itself to ground through r^{52} and completes circuit of R^{11} over path B, 19, 41, R^{11} , 42, r^{53} and ground. Relay R^{13} locks itself to battery through r^{131} , 43, r^{421} , 44, and 34 to B; connects battery to one terminal of relay R^{12} , through 34, 35, r^{133} , 45, 46, r^{152} , 47, and 48; and also completes circuit of rotary relay R^{18} through r^{132} and interrupter I, so that this relay is energized intermittently, its circuit being: B, 34, 35, r^{133} , 45, 46, r^{152} , 47, 49, 50, R^{18} , 51, r^{121} , 52, r^{132} , I to ground. At each actuation of relay R^{18} magnet M^5 is energized by current from B, 34, 57, contacts 58 of foot step switch F^4 , 59, M^5 , 53, r^{181} , ground, stepping primary selector switch S^4 around until wiper w^{26}

engages row test contact c^{26} whereupon relay R^{12} is energized over circuit B (Fig. 3) 34, 35, r^{133} , 45, 46, r^{152} , 47, 48, R^{12} , 49', w^{26} , c^{26} , (Fig. 2) 26, r^{31} , ground to battery. Relay R^{12} locks itself to ground through r^{122} , connects test wiper w^{25} to sleeve relay R^{15} through 54, r^{123} and 55, and shifts interrupter I from rotary relay R^{18} to vertical relay R^{19} at r^{121} , so that R^{19} is intermittently energized over the circuit: B, 34, 35, r^{133} , 45, 46, r^{152} , 47, 49, R^{19} , 56, r^{121} , 52, r^{132} , I, ground, to battery. At each actuation of relay R^{19} vertical magnet M^6 is energized over the path B, 34, 60, M^6 , 61, r^{121} to ground, stepping switch S^4 up until wiper w^{25} engages individual test contact c^{25} (Fig. 2) whereupon sleeve relay R^{15} is energized over the circuit: B, (Fig. 3), 34, 35, 62, R^{15} , 55, r^{123} , 54, w^{25} , c^{25} , (Fig. 2), 25, r^{12} (of relay R'), ground to battery. Relay R^{15} connects battery to trunk conductor 7, by way of r^{251} , 63, 64, r^{141} , 65, and resistance r , and at the same time opens the circuit of relay R^{12} at r^{152} . Relay R^{12} opens circuit of vertical relay R^{19} and magnet M^6 is deenergized, which permits wiper w^{25} to stop on contact c^{25} , wipers w^2 and w^4 engaging contacts c^3 and c^4 , respectively. Tip relay R^{14} is now energized through subscriber's telephone in series with R^{15} . Simultaneously with the selection of the calling line as described, distributing switch S^2 , (Fig. 2) is stepped around in search of an idle secondary selector, by magnet M^2 in circuit: B, 19, 41, 66, 67, 68, r^{21} , 69, M^2 , 70, r^{111} , 71, I to ground. Switch S^2 continues to step around until wiper arm ws^{200} engages a contact s^{200} connected to an idle secondary selector, whereupon relays R^{16} and R^{52} , (Figs. 2 and 5) are energized in series, the circuit being: B, (Fig. 5), 86, springs 73-74 of operator's jack J, 75, springs 76-77 of foot step switch F^8 , 78, R^{32} , 79, through Fig. 3 into Fig. 2, s^{200} , ws^{200} , 80, 81, R^{16} , 82, r^{112} to ground. The actuation of relay R^{16} causes the energization of relay R^9 , the circuit being: B, 19, 41, 66, 67, r^{101} , 83, 84, R^9 , 85, r^{113} to ground. Relay R^9 locks itself to battery through r^{92} , and opens circuit of magnet M^2 at r^{91} , whereupon switch S^2 comes to rest with wiper arms ws^2 , ws^{20} , and ws^{200} resting on contacts s^2 , s^{20} , and s^{200} , respectively. The attraction of armature r^{21} of relay R^8 connects battery to wire 99 which completes part of the row test circuit and the attraction of armature r^{93} completes the circuit of relay R^8 as follows: B, to R^8 , 223, r^{93} to ground. Relay R^8 grounds wire 80, shunting relay R^{10} out of series with relay R^{32} (Fig. 5) the circuit of the latter relay now going direct to ground by way of wire 80 and armature r^{82} . Relay R^{32} (Fig. 5) completes the circuit of rotary relay R^{19} through interrupter I so that said relay is intermittently energized by current over B, 86, 87, r^{361} , 130

88, r^{31} , 89, R^{21} , 90, r^{21} , 1 to ground. Relay R^{21} also connects one terminal of relay R^{30} to ground through 91 and r^{22} , and locks itself to battery through 92, r^{32} , 93, r^{202} , 87, 86, B. Each actuation of relay R^{30} energizes vertical magnet M^{12} through B, 86, 94, 114, r^{21} to ground. Magnet M^{12} steps switch S^1 up until wiper w^{22} engages contact s^{22} . The first rotary step of the switch S^1 disconnects contacts 76 and 77 of switch P^1 and connects contacts 76 and 290, which opens the initial energizing circuit of relay R^{21} (that relay, however, remaining energized through its locking circuit) and also opens the circuit of off-normal lamp 17 as follows: B, 86, 93, 74, 75, 76, 290, 17 to ground. When wiper w^{22} engages contact s^{22} the relay R^{21} is energized over the path: B, ground to r^{22} (of relay R^{32}), 91, 96, R^{31} , 29, 97, w^{22} , s^{22} , 98, through Fig. 3 into Fig. 2, s^{20} (in switch S^1), w^{22} , 95, r^{21} , 68, 67, 66, 41, 19, battery. Relay R^{21} locks itself to battery through 100, r^{212} , 101, 88, r^{301} , 87 and 86, opens circuit of relay R^{30} and closes circuit of relay R^{21} at r^{211} . Relay R^{21} opens circuit of magnet M^{12} at r^{211} , which stops switch S^1 with wiper w^{22} engaging contact s^{22} . As circuit of relay R^{21} is completed at r^{211} said relay is intermittently energized through: B, 86, 87, r^{21} , 88, r^{210} , 102, R^{40} , 103, 90, r^{211} , 1, ground. Each actuation of relay R^{21} energizes vertical magnet M^{14} through: B, 86, M^{12} , 104, r^{21} , ground. Magnet M^{14} steps switch S^1 up until wiper w^{24} engages contact s^{24} , whereupon relay R^{30} is energized through: B, ground to r^{22} (relay R^{32}), 91, B, 93, 103, w^{24} , s^{24} , 45, (Fig. 3), r^{21} , 155, 34, battery. Relay R^{30} opens locking circuit of relay R^{21} at r^{212} , also opens circuit of relay R^{21} at r^{211} . r^{211} of relay R^{21} opens vertical magnet M^{12} which stops switch S^1 with wipers w^{20} , w^{21} , w^{22} , and w^{24} on contacts s^{20} , s^{21} , s^{22} and s^{24} . (Wiper w^{21} is raised off row contacts by first step.) Wiper w^{22} engaging contact s^{22} (Fig. 5) relays R^{21} and R^{21} (Figs. 2 and 3) are energized through: B, (Fig. 3), 34, 35, 36, r^{211} , 63, 106, R^{21} , 107, (Fig. 5), r^{211} , w^{22} , 108, r^{211} , 109, r^{212} , 111, 112, R^{21} , 113, r^{211} , 114, r^{211} , 115, r^{212} , 116, r^{212} , ground.

Relay R^{21} , when actuated, opens series circuit of relays R^8 and R^{11} (Figs. 2 and 3) at r^{211} . Relay R^{11} disconnects interrupter I^1 at r^{212} and relay R^8 (Fig. 2) opens circuit of relay R^8 at r^{211} . Relay R^8 deenergizing opens circuits of magnet M^8 , relay R^8 and relay R^{11} , while relay R^8 , its circuit opened at r^{211} , opens circuit of stepping magnet M^8 at r^{211} . This prepares distributing switches S^1 and S^2 with their relays, for author call. Relay R^{21} becoming energized closes circuit of night alarm N through: B, 86, 110, 117, 118, r^{211} , 119, N, to ground; closes circuit of guard lamp L^2 (Fig. 6) through B (Fig. 5), 86, 116, 117, 118, r^{212} , 129, 121,

(121 Fig. 6), L^2 to ground; closes circuits of service meter E (Fig. 5) through B, armature r^{201} , 122, 212, and magnet of service meter E to ground; and line lamp L^2 (Fig. 6) through B (Fig. 5), r^{201} , 122, 70, 123, (123 Fig. 6), L^2 to ground. The operator, preceding the signal, depresses listening key LK (Fig. 6) energizing listening relay R^{22} (Fig. 6) through: B, (Fig. 5), 86, 87, r^{211} , 88, 101, r^{211} , 121, R^{22} , 125, 76 (125 Fig. 6), contacts of key LK , 126 to ground. Relay R^{22} energizing, opens series circuit of relays R^8 and M^{12} at r^{211} and locks itself to ground through r^{211} and also as previously stated. Relay R^{22} deenergizing, 86 opens circuit of relay R^8 at r^{211} . Relay R^{22} completes the operator's listening circuit as follows: receiver OR, 127, ph. P, tip p, spring j, 128, r^{211} , 129, 131, r^{201} , s, 130, (130 Fig. 5), r^{211} , 133, 9, r^{212} , 7, condenser 85 C, 5, w^{21} , s^{21} , (Fig. 2), 3, r^{21} , line wire 1, subscriber's telephone, free wire 2, r^{212} , 291, 4, r^{21} , w^{21} , (Fig. 3), 4, condenser C², s, r^{211} , 10, 131, r^{212} , 135, (135 Fig. 5), s^{21} , w^{21} , 132, 136, r^{212} , 137, coil 1C, 138, pick spring j, phag 90 sleeve p¹, 139, receiver OR.

Should the calling subscriber hang up his receiver before the operator is connected, tip relay R^{14} (Fig. 2) is deenergized, its circuit being open at the subscriber's switch 65 hook contact, and sleeve relay R^{15} remaining energized in series with cut-off relay R^2 (Fig. 2), energizing circuit of relay R^{28} (Fig. 5) is completed as follows: B, (Fig. 5) 34, 35, 36, r^{211} , 63, 64, r^{211} , 65, through resistance r , trunk conductor T, r^{212} , 9, 133, r^{211} , 130 (130 Fig. 5), s^{20} , w^{20} , 131, 129, r^{211} , 128, 154, R^{28} to ground. Relay R^{28} energizing, connects operator's tone-test circuit T_2 through 155 and 137 to operator's receiver, 105 and the operator being thus notified that the calling subscriber has disconnected, actuates the "release and trunk start" key RK (Fig. 6) whereupon relay R^{21} (Fig. 5) receives current through: B, 86, 116, 156, R^{21} , 157, 110 (157 Fig. 6) key RK to ground. R^{21} then energizes starting relay R^{211} in series with relay R^{12} (Fig. 3) through: B, (Fig. 3), 34, 35, 36, r^{211} , 63, 106, r^{212} , 107, (107 Fig. 5), s^{21} , w^{21} , 108, r^{211} , 109, r^{212} , 111, 111, R^{21} , 110, 115, r^{211} , 116, r^{212} , ground through RK . Relay R^{21} energizes relay R^{11} which through armatures r^{211} and r^{212} connects impulse sending wires 120 and 135 to tip and sleeve conductors 9 and 10 respectively. The circuit of relay R^{21} is: B, 34, 44, r^{211} , 142, R^{21} , 143, contacts 144 and 145 of foot-step switch F^5 to ground. Relay R^{21} being energized, opens the locking circuit of listening relay R^{22} at r^{211} and locks itself through 148, r^{211} , 125, 115, r^{212} , 116, r^{212} , to ground; and also establishes a locking circuit for relay R^{21} through 159, r^{211} , 158, 140, 148, r^{211} to ground over the same path traced for locking circuit of relay R^{21} . Armature r^{212} closes circuit of 130

- guard lamp L^2 (Fig. 6) through: B, (Fig. 5), 86, 110, 117, 149, r^{362} , 150, 121, L^2 to ground, and armature r^{363} partially closes circuit of magnet M^{15} so that when cam disk 5 D^{11} (Fig. 6) closes contacts d^{11} , said magnet is momentarily energized, stepping switch S^3 forward one step. The circuit of magnet M^{15} is: B, (Fig. 5), 86, 110, 117, M^{15} , 153, r^{353} , 152, r^{363} , starting wire 151, (151 Fig. 6), 10 contacts d^{11} , to ground.
- Immediately after switch arm ws^3 engages contact $1s^3$, a number of ground impulses come from the sending machine over wire 173. A sending machine having interlocking keys is used, and one of the keys is always down. If such a sending machine were not used, it is intended that the operator press down one key of the row to which wire 173 leads, or else press down some 15 equivalent key resulting in the transmission of impulses from the commutator device I by way of contact $1s^3$, wiper arm ws^3 , trunk-conductor 131, ws^0 , s^0 , 130, (130 Fig. 3), r^{411} , 174, relay R^{21} to battery and ground. 20 Each actuation of relay R^{21} closes circuit of magnet M^8 at r^{211} , which steps the switch S^5 forward one step, springs 175 and 176 of switch F^5 being closed at the first rotary step. The closure of springs 175 and 176 25 energizes release magnets M^8 and M^4 of the primary and first selector switches S^4 and S^5 , through 106, 177, r^{42} , 178, 179, M^8 and M^4 in multiple, B. These magnets restore their respective switches to normal position. 30 The circuit of sleeve relay R^{15} is now open at w^4 , and its armature r^{151} , opens the series circuit of relays R^{42} , and R^{36} (Figs. 3 and 5). Relay R^{36} opens at r^{361} the locking circuit of relay R^{37} . As wiper arm ws^{300} is 35 resting on contact $1s^{300}$ and armature r^{362} of relay R^{36} is retracted, the retraction of armature r^{372} , of relay R^{37} , closes circuit of relay R^{35} as follows: B, 86, 110, 117, 149, r^{362} , 163, 161, r^{372} , 293, $1s^{300}$, ws^{300} , 164, R^{35} to ground. 40 Armature r^{368} of relay R^{35} connects one terminal of stepping magnet M^{15} to interrupter I for intermittent energization over the path: B, 86, 110, 117, M^{15} , 153, r^{353} , 165, I, to ground. Magnet M^{15} steps around 45 switch arms ws^3 , ws^{30} and ws^{300} over their respective bank contacts. After wiper arm ws^{300} leaves contact $2s^{300}$ and sweeps over contacts $3s^{300}$ to $5s^{300}$ relay R^{35} is kept energized through B, 86, 110, 117, 149, r^{362} , 163, 50 162, contacts $3s^{300}$ to $5s^{300}$, ws^{300} and so on as previously traced. When wiper ws^{300} reaches contact $6s^{300}$ the circuit of relay R^{35} is again changed and said relay is energized while the arm sweeps over contacts $6s^{300}$ to $9s^{300}$, 55 through: B, 86, 110, 166, $6s^{300}$ to $9s^{300}$, ws^{300} , 164, and so on as previously traced. When wiper arm ws^{300} passes off the last contact $9s^{300}$ it opens the circuit of relay R^{35} , which disconnects magnet M^{15} from interrupter I 60 at r^{358} , and stops switch S^8 with its wiper 65 contacts d^{11} , to ground.
- arms ws^3 , ws^{30} and ws^{300} , clear of all contacts. Shortly before switch S^3 comes to normal position, contact springs 167 and 168 are momentarily closed by a cam on the switch spindle and release magnet M^{16} is 70 energized through: B, 86, 169, 170, M^{16} , 171, 172, 167, 168, ground. Magnet M^{16} restores switch S^3 to normal position, ready for another call.
- If the calling subscriber remains on the 75 line, the operator, on ascertaining the number wanted sets up the same on her key set, (Fig. 6,) by depressing the key in strip K corresponding to the first digit, that in the strip K^2 corresponding to the second digit, 80 that in the third strip K^3 corresponding to the third digit, and that in the strip K^4 corresponding to the particular ringing generator to be selected, and then actuates starting key, SK, whereupon starting relay R^{36} 85 (Fig. 5) is energized in series with trunk cut-off relay R^{42} (Fig. 3) through: ground, 126, (Fig. 6) key SK, 140, (140 Fig. 5) R^{36} , 141, 111, r^{351} , 109, r^{313} , 108, ws^3 , s^3 , 107, (107 Fig. 3), R^{42} , 106, 63, r^{151} , 35, 34, battery to 90 ground. Relay R^{42} opens trunk conductors 9—7 and 10—8 at r^{422} and r^{423} , and energizes relay R^{41} through: B, 34, 44, r^{211} , 142, R^{41} , 143, contacts 144 and 145 of switch F^5 to ground. Armatures r^{411} and r^{412} connect the 95 impulse wires 130 and 135 to rotary and vertical relays R^{21} and R^{20} , respectively, while armature r^{413} connects conductor 147 to one terminal of relay R^{41} through contact 146. Starting relay R^{36} (Fig. 5) takes 100 ground off relay R^{33} through 114, at r^{361} , and locks itself through 148, r^{361} and 115 to ground as previously traced. Armature r^{362} maintains the circuit of the guard lamp through B, 86, 110, 117, 149, r^{362} , 150, 121, 105 guard lamp to ground, as previously traced. Armature r^{363} connects starting wire 151 to stepping magnet M^{15} through: B, (Fig. 5) 86, 110, 117, M^{15} , 153, r^{353} , 152, r^{363} , starting wire 151, (151 Fig. 6) contact springs d^{11} , 110 to ground; so that when cam disk D^{11} (Fig. 6) closes contacts d^{11} , said magnet is momentarily energized, stepping switch S^3 forward one step. Immediately after cam D^{11} (Fig. 6) has passed under the contacts d^{11} , 115 the number cams D' to D^{10} inclusive, pass under their respective contact springs d' to d^{10} inclusive, the cam D' maintaining the closure of contact d' during one closure of the interrupter contact springs d^1 , the cam 120 D^2 maintaining the closure of its contact springs d^2 during two closures of said interrupter contacts, and so on to the cam D^{10} , which maintains the closure of its contact springs d^{10} during ten closures of the 125 interrupter contact springs. During the passage of the number cams under their contact springs, ground impulses (corresponding in number to the first digit of the wanted line) are sent over the hundreds impulse wire 173 130

to the rotary relay R^{21} of the first selector switch S^5 (Fig. 3). Assuming for example, that the number wanted is 246-3, relay R^{21} will be momentarily energized two times, through: ground, d^1 , 190, d^2 , 191, 192, 193, k^{24} of strip K^2 , 173, (173 Fig. 5) 18³, ws^3 , 131, ws^{20} , 130, (130 Fig. 3), r^{111} , 174, R^{21} , battery B to ground. Relay R^{21} intermittently energizes magnet M^3 which steps switch S^5 to the second row of contacts through which the connector containing wanted subscriber's line is accessible. At the first rotary step of switch S^5 , contact springs 175-176 are closed, completing the circuit of "off normal" lamp L^5 through B, 103, 104, L^5 , 105, 106, 176, 175 to ground; also partially closing the release circuit through magnets M^3 and M^4 , hereinafter described. After the number cams have passed under their respective springs cam D^{11} again closes its contacts d^{11} stepping switch S^5 around to bring its wipers into engagement with the next set of contacts. Wiper arms ws^7 , ws^{20} and ws^{200} of switch S^5 now engage their respective contacts $2s^3$, $2s^{20}$, and $2s^{200}$, and cam D^{12} (Fig. 6) connects test impulse wire 189 through springs d^{12} , conductor 190 and springs d^1 to ground during ten closures of springs d^1 , whereupon vertical relay R^{20} (Fig. 3) is intermittently energized through: ground, d^1 , 190, d^{12} , 189, (189 Fig. 5), $2s^3$, ws^{20} , 132, ws^1 , s^1 , 135, (135 Fig. 3), r^{112} , 199, R^{20} , 196, battery, to ground. Relay R^{20} intermittently closes circuit of magnet M^1 at r^{201} , stepping up wipers w^8 , w^{16} and w^{147} of the first selector switch S^5 to engage contacts c^{13} , c^{14} and c^{200} , respectively, leading to a connector trunk (Fig. 4). At the first vertical movement of the spindle of switch S^5 the circuit of relay R^{21} is opened at contact springs 144 and 145 of switch F^5 , and should the connector trunk (Fig. 4) be busy because of the wipers of another first selector switch resting on the multiples of contacts c^{200} , relay R^{21} would remain energized through B (Fig. 3), 34, 44, r^{421} , 142, R^{21} , 146, r^{412} , 147, w^{147} , c^{200} (Fig. 4) to the multiples of c^{200} and thence through the circuit of the other first selector by way of its wiper w^{147} (as in Fig. 3), 147, r^{413} , ground, to battery.

The armature r^{412} of relay R^{21} , remaining attracted permits the next test impulse to energize vertical relay R^{20} stepping the wipers up to the next set of contacts, and so on until an idle connector is reached, when, relay R^{21} being deprived of ground, releases its armatures. The armature r^{412} , disconnects impulse wire 135 from the relay R^{20} , stopping switch S^5 with its wipers w^9 , w^{16} and w^{147} on contacts c^{13} , c^{14} and c^{200} , respectively, of the connector trunk (Fig. 4). The impulse wires 130 and 135 are now connected to the tip and sleeve conductors 9 and 10 through armatures r^{411} and r^{412} respectively, and con-

tact c^{200} (Fig. 4) and its multiples are connected to ground through: w^{147} , (Fig. 3), 147, and r^{413} . After cam D^{12} (Fig. 6) has passed springs d^{12} , starting cam D^{11} again closes springs d^{11} , steps switch S^5 around to bring its wipers into engagement with the third set of contacts. Wiper arms ws^3 , ws^{20} and ws^{200} now engage contacts $3s^3$, $3s^{20}$ and $3s^{200}$, respectively. The number cams now pass under their respective contact springs for the third time and send impulses, corresponding in number to the desired ringing generator (in this case No. 3), to relay R^{23} (Fig. 4), through: ground, springs d^1 (Fig. 6), 190, d^2 , 198, 203, k^{24} , 197, (197 Fig. 5), 80 $3s^3$, ws^3 , 131, ws^{20} , s^{20} , 130, (130 Fig. 3), r^{411} , 133, 9, w^9 , c^{13} , (Fig. 4), 16, r^{201} , 204, R^{23} , 205, B to ground. Each actuation of relay R^{23} energizes magnet M^{11} of switch S^7 , through: B, 206, 208, 209, 210 and 211, 212, 213, M^{11} , 85 214, 215, r^{231} to ground. Magnet M^{11} moves switch S^7 forward three steps, bringing wipers ws^7 , ws^{70} and ws^{700} onto contacts $3s^7$, $3s^{70}$ and $3s^{700}$ respectively.

The first actuation of R^{23} energizes R^{24} 90 and R^{27} , the first through: B, 206, 207, 205, r^{231} , 247, R^{24} , 202, 200, c^{200} , w^{147} , (Fig. 3) 147, r^{413} to ground, locking itself to battery through 249, r^{241} , 250, r^{222} , 207; the second relay through: B, r^{252} (of relay R^{25}), 234, 95 230, R^{27} , 235, r^{252} , 236, 202, to ground, locking itself to battery through: 232, r^{271} , 233, r^{291} , 231. Cam D^{11} (Fig. 6), again closing contacts d^{11} moves switch S^5 one step bringing its wipers onto the fourth set of contacts. 100 Wiper ws^{30} now engages contact $4s^{30}$ and the number cams close their respective springs and send impulses to R^{22} (Fig. 4) through: ground, contacts d^1 , (Fig. 6) 190, d^4 , 225, 226, 227, k^{24} of strip K^2 , 224, (224 Fig. 5), 105 $4s^{30}$, ws^{20} , 132, ws^1 , s^1 , 135, (135 Fig. 3), r^{412} , 134, 10, w^{16} , c^{14} , (Fig. 4) 15, r^{261} , 228, R^{22} , 229, 230, 232, r^{271} , 233, r^{291} , 231, battery to ground. Each actuation of R^{22} energizes magnet M^9 through: B, 206, 208, 237, 238, 110 239, M^9 , 240, r^{221} , ground. Magnet M^9 moves switch S^6 forward four steps bringing wipers w^{17} and w^{18} onto the fourth row of contacts, in which lie the wanted line contacts.

The first actuation of R^{22} opens the locking circuit of R^{24} at r^{222} . The first rotary step opens springs 210-211 and closes 210-216, which shifts battery lead 209 from M^{10} to M^{10} and lights lamp L^6 by current 120 through: B, 210, 246, 245, 264, 266, r^{283} , 248, L^6 to ground. Cam D^{11} (Fig. 6) again closes contacts d^{11} and sends one impulse over wire 151, actuating switch S^5 to step its wipers onto their fifth set of contacts. After cam 125 D^1 has passed contacts d^{11} , the number cams again actuate their respective spring contacts sending unit impulses through 241, 131 (Fig. 5), wiper ws^7 , $5s^3$, to R^{23} (Fig. 4). Each actuation of relay R^{23} energizes M^{10} , 130

through: B, 206, 208, 209, 210, 246, 245, 244, M¹⁴, 243, w²⁷², 215, r²³¹, to ground. Magnet M¹⁵ is actuated six times, stepping wipers w¹⁷ and w¹⁸ onto contacts c¹⁷ and c¹⁸ (Figs. 4 and 5 respectively). The first actuation of relay R²³ again energizes R²⁴ through r²³³ and R²⁴ locks itself and disconnects R²⁵ and R²⁶ from wipers w¹⁷ and w¹⁸, at r²⁴³ and r²⁴¹ to prevent affecting said relays while the wipers are passing over other line multiples. After the number cams pass their springs, and before cam D¹¹ closes its springs, cam D¹⁵ closes springs d¹⁵, sending a single test impulse through 292, 5s³⁰, w³⁰, 15 and 132 (Fig. 5) to R²² (Fig. 4), whereupon if the wanted line (Fig. 7) is busy, with wipers w¹⁷, w¹⁸, of another connector switch, or w⁴ of a primary selector switch, resting on multiples of contacts c¹⁷, c¹⁸, the test relay R²³ (Fig. 4) is energized, in the first case through: ground, r²¹² (Fig. 3), 147, w¹⁷, c²⁶² (Fig. 4), 200, 201, R²⁵, 251, r²²³, 292, r²⁸¹, 253, 18, w¹⁸, c¹⁸ (Fig. 7) to the multiple of c¹⁸ on which the other connector switch wipers are resting, thence through that connector by way of w¹⁸, 18, 253, r²⁸¹, 252, r²²³, 259, R²⁶, 260, 261, r²⁴¹, 250, r²²², 207, B, to ground; in the second case through: ground, R²⁵, c¹⁸, thence through the multiple of c¹⁸, on which wiper w⁴, of a primary selector is resting, 294, r²³, 55, R¹⁵, 62, 35, 34, B, to ground. Relay R²³ when energized re-locks itself to battery through 262, r²³¹, connects the busy back B₂ to trunk conductor 16, through r²³² and 263, and closes the release circuit of S⁶ through: B, 206, 208, 209, 210, 246, 245, 264, 265, r²⁹³, 267, 269, M¹² to ground. M¹² then releases the connector switch S⁶. After this impulse relay R²³ is de-energized, and completes the restoring circuit of switch S¹ through: B, r²²², 250, r²⁴¹, 261, 270, r²³², 271, r²⁵¹, 272, 213, M¹¹, 214, r²⁷², 273, w³⁰, s⁷⁰, 274, I to ground.

Magnet M¹¹ is intermittently energized until switch S⁷ reaches normal position when its circuit is opened between w³⁰ and s⁷⁰. The test relay R²³ remains locked, holding busy-back B₂ on trunk conductor 16, to signal the calling subscriber, (Fig. 2), who then hangs up his receiver, opening circuit of R¹⁴ (Fig. 3) which energizes and releases magnets M³ and M⁴ of switches S⁴ and S⁵ through ground, 173, 176, 106, 177, r¹¹², 178, 179, M³ and M⁴, (in multiple), B, to ground. The switch S⁵ in restoring opens the circuit of R²³ (Fig. 4) at r²³⁰ and w¹⁷ (Fig. 3) and the busy-back is disconnected. If the wanted subscriber is not busy, R²³ remains locked, and after the test impulse R²³ de-energizes, which energizes R²⁶ (Fig. 4) and R⁴³ (Fig. 7) in series, through: B, (Fig. 4) r²²², 250, r²⁴¹, 261, 260, R²⁶, 259, r²²³, 259, r²⁸¹, 253, 18, w¹⁸, c¹⁸, (Fig. 7) 255, R⁴³ to ground. Relay R²⁶ closes trunk conductors 15—17 and 16—18 at r²⁶² and r²⁶¹, respectively, while R⁴³ (Fig. 7) connects line terminals 256 and 257 to extensions 254 and 255. Simultaneously with the energization of R²⁶ and R⁴³, ringing relay R²⁸ is connected through: B, r²³², 250, r²⁴¹, 261, 270, r²⁷³, 277, 70 r²³², 273, R²⁸, interrupter I² to ground. Immediately after the test impulse cam D¹¹ (Fig. 6) causes contacts d¹¹ to send an impulse over wire 151, stepping switch S³ (Fig. 5) forward one step bringing its 76 wipers onto the sixth contact set. When w³⁰ engages contact 6s³⁰⁰, the restoring relay R³⁵ is energized through: B, 86, 110, 166, 6s³⁰⁰, to 9s³⁰⁰, w³⁰⁰, 164, R³⁵, to ground. Relay R³⁵ opens circuit of R³⁰ and R⁴², (Figs. 5 and 3 respectively) at r³⁵¹ and r³⁵², while r³⁵³ connects magnet M¹⁵ for intermittent energization through: B, 86, 110, 117, M¹⁵, r³⁵³, 165, I to ground. Magnet M¹⁵ steps switch S³ forward, holding R³⁵ energized through w³⁰⁰ and contacts 6s³⁰⁰ to 9s³⁰⁰, until the wipers have reached normal position, as shown. The secondary selector switch S⁵ is restored by the cam on the switch S³, in passing, and the operator's circuit is ready to receive another call.

Ringing relay R²⁸ is intermittently energized by interrupter I² to ring subscriber A³, (Fig. 7) through circuit: G³, 279, 3s⁷⁰, w³⁰, 280, r²⁸², 281, 17, w¹⁷, c¹⁷, (Fig. 7) 254, r⁴³¹, 256, 282, ringer O³, C³⁰, 283, 257, r⁴³², 258, 255, c¹⁸, w¹⁸, (Fig. 4) 18, 253, r²⁸¹, 284, resistance r', 285, 208, 206, B to ground and generator G³. At each energization of relay R²⁸ the circuit of lamp L³ is opened at r²⁸³. When the called subscriber A³ takes down his receiver, he bridges his telephone across the line, and at the next non-ringing interval the circuit of the tip relay R²⁸ is closed through: B, (Fig. 4) through R²⁶ to c¹⁸ (Fig. 7), 255, r⁴³², 257, 283, H³⁰, telephone at A³, 286, 256, r⁴³¹, 254, c¹⁷, w¹⁷ (Fig. 4), 17, 281, r²⁸², 287, R²⁸, 288, r²⁴³, 275, r²²¹ to ground. Relay R²⁸ opens circuit of R²⁷ at r²⁵², relay R²⁷ opens circuit of ringing relay R²⁸ at r²⁷¹, and the ringing ceases. The calling and called subscribers A and A³, respectively, are now connected for conversation over the circuit indicated in heavy lines in Figs. 2, 3, 4 and 7. Relay R²⁵ connects test contact c²⁶⁰ through: c²⁶⁰, 200, 202, 236, r²⁵², to ground side of battery, which renders the trunk busy in case the calling party should hang up first. At the end of the conversation, when calling subscriber A hangs up his receiver the circuit of the tip relay R¹⁴ (Fig. 3) is opened, whereupon armature r¹⁴², falling back, closes the circuit of release magnets M³ and M⁴ of the switches S⁴ and S⁵, which return to their normal position. When called subscriber A³ hangs up his receiver, the circuit of tip relay R²⁵ (Fig. 4) is opened, whereupon armature r²⁵¹, falling back, completes the restoring circuit of switch S⁷, said switch is restored, and when

wiper arm ws^7 engages contact $9s^7$ (which occurs just before the switch reaches its normal position) the circuit of release magnet M^{12} is completed as follows: battery B, 5 206, 207, 289, ws^7 , $9s^7$, 290, 269, M^{12} , ground, to battery. The connector switch S^6 then returns to its normal position.

Having thus described my invention, what I claim and desire to secure by Letters Patent is:

1. In a telephone exchange system, a plurality of line circuits, switching apparatus for effecting interconnection thereof, an operator's circuit, means for effecting an initial connection of a line when calling to said operator's circuit, an operator's telephone, means to connect the same with the operator's circuit after said initial connection, and a signal device actuated only when the operator's telephone is so connected.
2. In a telephone exchange system, a plurality of line circuits, switching apparatus for interconnecting the same, an operator's circuit, means for effecting the initial connection of a line when calling to said operator's circuit, a called signal associated with the operator's circuit and adapted to be displayed to indicate the call, an operator's telephone, means to connect said telephone to the operator's circuit in response to the call, and a supplemental signal associated with said connecting means and adapted to be displayed only when the telephone is so connected.
3. In a telephone exchange system, a plurality of line circuits, switching apparatus for interconnecting them, an operator's equipment circuit, automatic means for effecting the initial connection of said circuit with a line when calling, a signal associated with said circuit and adapted to be automatically displayed when it is so connected, an operator's telephone, means for connecting the same to the operator's circuit, and a supplemental signal device adapted to be automatically displayed when the telephone becomes so connected.
4. In a telephone exchange system, a plurality of line circuits, switching apparatus for interconnecting the same, and operator's equipment circuit, automatic means for effecting an initial connection of said circuit with a line when calling, a relay adapted to become energized upon the completion of said connection, a called signal device controlled by said relay, an operator's telephone normally disconnected from said circuit, means for connecting the telephone in response to the indication of the signaling device, and a supplemental signal device controlled in the actuation of said connecting means.
5. In a telephone exchange system, a plurality of line circuits, automatic switching

apparatus for interconnecting the same, an operator's circuit, means for effecting the initial connection of said operator's circuit with a line when calling, an operator's telephone, means for connecting the same to the operator's circuit in response to a call, connection from said operator's circuit to the automatic switching apparatus, actuating means for said switching apparatus adapted to be controlled through the operator's circuit, a signal device adapted to be automatically displayed when the said telephone becomes connected with the operator's circuit, and a second signal device becoming displayed upon the initial operation of said switch actuating means.

6. In a telephone exchange system, a plurality of line circuits, automatic switching apparatus for interconnecting the same, an operator's circuit, automatic means for effecting initial connection of said operator's circuit with a line when calling and with said automatic switching apparatus, an operator's telephone, means for connecting the same to said operator's circuit, a signal device becoming automatically displayed when the telephone is so connected, a selective controlling device for the automatic switching apparatus, starting means therefor, means for connecting the same to the operator's circuit and thence to the automatic switching apparatus, and a signal device becoming displayed in the operation of the starting means.

7. In a telephone exchange system, a plurality of line circuits, automatic switches for interconnecting the same, an operator's circuit, automatic means for effecting initial connection of said operator's circuit with a line when calling and with the automatic switches, an operator's telephone, a listening key, a lamp signal controlled by said listening key, an impulse sending device for the switches, a starting button therefor, and a second signal device controlled by said starting button.

8. In a telephone exchange system, a plurality of line circuits, automatic switching apparatus for interconnecting the same, an operator's circuit, means for effecting initial connection of said circuit with a line when calling and with the automatic switching apparatus, a call signal associated with the operator's circuit and becoming displayed on the completion of said initial connection, an operator's telephone, means for connecting the same with said circuit in response to a call, a second signal device becoming displayed on said connection of the telephone, a selective controlling device for the automatic switching apparatus, starting means therefor and a third signal device becoming displayed on the actuation of said starting means, whereby the progress of an opera-

- tor's work in handling a call, and the condition of the equipment at each step may be accurately observed and supervised.
9. In a telephone exchange system, a plurality of line circuits, link circuits for interconnecting the same, automatic primary selector switches at one extremity of the links responsive to calls over the lines to connect the links thereto, automatically driven selector and connector switches adapted when properly actuated to advance the connection of their respective links to the terminals of wanted lines, so as to complete connections initiated through the primary selectors, an operator's trunk circuit common to a plurality of lines and links, a secondary selector switch containing terminals of the primary links, and adapted to connect the operator's trunk to a calling line and to the driven selective switches, a calling lamp signal associated with said secondary selector switch, means to light the same upon the initial establishment of connection between a calling line and the operator's trunk, an operator's telephone, a listening key adapted to connect the same to said trunk, a supplemental signal lamp having its circuit closed in the operation of said listening key, a sending machine adapted to supply current impulses for the driven switches, a plurality of number keys adapted to select impulses from the sending machine in groups corresponding to the numbers to which the driven switches are to be impelled, means for connecting said number keys and the operator's trunk to the sending machine at the beginning of a cycle of operation thereof only, a starting key for said connecting means, and a third lamp signal arranged to have its circuit closed in the operation of said starting key; whereby first the operator's trunk and "key set" will become automatically connected to a calling line and the corresponding call signal displayed; second the operator when listening will have an indication and will give the supervising authority through the listening lamp an indication of the progress of the call; and third after the starting key is depressed, and the impulses are being transmitted to the driven switches as determined by the operator in response to the requirements of the calling subscriber, an indication will be given to the operator and to the supervisory authority that the particular key set and trunk involved are in use, that the operation of the mechanism is normal, and upon the extinguishment of the lamp that it is again available for another call.
10. In a telephone exchange system, a plurality of line circuits, connective means controlled over the line circuits to effect initial connection therewith in response to calls, an operator's telephone, a call signal associated with the operator's telephone, means for connecting said telephone with the connective means and line, and signaling means then becoming operative to indicate to the operator the condition of the line.
11. In a telephone exchange system, a plurality of line circuits, connective means controlled over the line circuits to effect initial connection therewith in response to calls, an operator's telephone, a call signal associated with the operator's telephone, means for connecting said telephone with the connective circuit and line, and a supplemental signal with controlling means therefor responsive to the condition of the line at that time.
12. In a telephone exchange system, a plurality of line circuits, connective means controlled over the line circuits to effect initial connection therewith in response to calls, an operator's telephone, a call signal associated with the operator's telephone, means for connecting said telephone with the connective circuit and line, and a supplemental signal device with a controlling relay responsive to the then condition of the line.
13. In a telephone exchange system, a plurality of line circuits, connective means controlled over the line circuits to effect initial connection therewith in response to calls, an operator's telephone, a call signal associated with the operator's telephone, means for connecting said telephone with the connective circuit and line, and a tone test signal, with a controlling relay dependent upon line current for its energization, and adapted to connect the tone test to the operator's telephone circuit if the line is open or disabled when the telephone is connected to the connective circuit.
14. In a telephone exchange system, a plurality of line circuits, connective means controlled over the line circuits to effect initial connection therewith in response to calls, an operator's telephone, a call signal associated with the operator's telephone, means for connecting said telephone with the connective circuit and line, and a circuit interrupter adapted to produce a definite tone test, with controlling relays therefor, one of which is responsive to current flow in the subscriber's line, and the other to the act of the operator in connecting her telephone, whereby the operator will receive a special tone test signal if a subscriber's line is open when she listens in.
15. In a telephone exchange system, a plurality of line circuits, connective means controlled over the line circuits to effect initial connection therewith in response to calls, an operator's telephone, a call signal associated with the operator's telephone, means for connecting said telephone with the connective circuit and line, a tone test interrupter, a controlling relay therefor adapted when energized to connect the in-

terrupter to the operator's telephone, a circuit connection from said relay to the operator's connecting means, and a relay associated with the connective circuit so as to be responsive to current in the subscriber's line, and a current supply circuit controlled by said relay for the tone test relay, whereby the initial act of the subscriber in calling will suffice to effect the connection of his line with a connective circuit and with the operator, but in the event that he should restore his telephone to its normal connective condition, thereby changing the condition of the line circuit, the operator will be apprised of its changed condition by the tone test immediately upon listening in.

16. In a telephone exchange system, line circuits, automatic primary selecting means, an operator's telephone and switching means therefor, together with a special signal adapted to apprise the operator of the condition of a line when listening in.

17. In a telephone exchange system, a plurality of line circuits, a line relay for each line, a cut-off relay associated with each line relay, a self-locking circuit connection for each line relay passing through normally closed contacts of the associated cut-off relay, automatic primary selecting switches and link circuits adapted to be connected to the calling lines by said primary switches as determined by the energization of the line relays, a tip relay in each link circuit responsive to current in a connected line circuit, an operator's circuit with automatic means for connecting it to the link circuit, an operator's telephone, tone test, and switch contacts for listening in, together with a controlling relay for the tone test having its winding connected to said switching contacts so as to be brought thereby into connection with and under the control of the tip relay of the link circuit.

18. In a telephone exchange system, line circuits, link circuits for interconnecting the lines terminating at one end in primary selector switches containing line terminals, means for controlling said switches in response to calls over the lines to connect a calling line to an idle link circuit, an operator's circuit with automatic switching means to connect it to a link circuit when initially connected to a calling line, a tone test relay and an operator's telephone with a common switching device to connect them simultaneously to the operator's circuit, a testing relay in each link circuit responsive to current in a subscriber's line, and means controlled by said relay to change the potential on a conductor of the link circuit when a dead calling line becomes connected thereto, whereby switching of the operator's telephone and tone test relay into connection with the link will affect said tone test relay

and render the test signal audible to the operator.

19. In a telephone exchange system, a plurality of metallic circuit lines, metallic link circuits for interconnecting the same, each terminating at one end in the wipers of a primary selector switch, and each having its conductors conductively divided into two sections inductively connected for the transmission of speech waves, sleeve and tip relays with an interposed source of battery supply bridged across the primary switch sections of each link, a normally incomplete test potential wire connected through normally open contacts of the sleeve relay and normally closed contacts of the tip relay in series with the tip side of the second section of each link circuit, an operator's trunk circuit and switching mechanism adapted to connect the same with said second section of each link, an operator's telephone and a tone test relay, switching means adapted when actuated to connect the same in parallel with the second section of a connected link, and a tone test interrupter having its circuit connected through normally open contacts of the tone test relay with the operator's telephone, whereby the connection of the operator through any link circuit to a line then dead or without current, will cause the tone test relay to connect the tone test interrupter to the operator's telephone and produce therein a characteristic signal indicating the condition of the line.

20. In a telephone exchange system, line circuits, automatic switches for interconnecting the same, an operator's trunk circuit and secondary automatic switching mechanism for connecting the same to any one of a number of links when connected to a calling line, release mechanism for the secondary switching mechanism, an impulse sending machine with means for selecting and transmitting predetermined groups of impulses therefrom through the operator's trunk to the automatic switching mechanism of the links, progressively operating controlling mechanism associated with the operator's trunk circuit and determining the order of transmission of the impulses, and means controlled thereby for actuating the release mechanism of the secondary switching mechanism.

21. In a telephone exchange system, line circuits, automatic switches for interconnecting the same, an operator's trunk circuit and secondary automatic switching mechanism for connecting the same to any one of a number of links when connected to a calling line, release mechanism for the secondary switching mechanism, an impulse sending machine with means for selecting and transmitting predetermined groups of impulses therefrom through the operator's trunk to the auto-

- matic switching mechanism of the links, progressively operating impulse controlling mechanism associated with the operator's trunk circuit and determining the order of 5 transmission of the impulses, and means controlled by said controlling mechanism at the end of a complete cycle of impulses only, to actuate the release mechanism of the secondary switching mechanism.
- 10 22. In a telephone exchange system, line circuits, automatic switches for interconnecting the same, an operator's trunk circuit, a secondary switch adapted to connect the same with the said interconnecting switches, a release magnet for said secondary switch, a sending machine with means for selecting and transmitting predetermined groups of impulses therefrom through the operator's trunk to the interconnecting switches, a con-
- trolling step by step switch interposed between the sending machine and the operator's trunk and determining the order of transmission of the groups of impulses so as to effect complete operation of the interconnecting switches for each complete cycle 20 of impulses from the sending machine, and means operated in the last movement of said step by step switch to close the circuit of the release magnet of the secondary selector switch, to restore the same and disconnect 25 the operator's trunk from the interconnecting switches.
- 25 In testimony whereof I affix my signature in presence of two witnesses.
